UNITED STATES PATENT OFFICE

LUCIAN G. COBLE, OF GREENSBORO, NORTH CAROLINA

DENTAL ARTICULATOR

Application filed August 21, 1929. Serial No. 387,483.

This invention relates to improvements in dental articulators.

The primary object of the invention is to provide an articulator wherein there may be obtained a wider range of adjustment between the denture holder and the upper jaw without increasing the cost of the device or incorporating therein any complicated securing means for the jaws of the articulator. 10 A further object is to obtain wider range of adjustment by means that will permit altering the relation of the jaws of the articulator with greater care and without removal of any parts, thus preventing loss of parts 15 and a saving in time.

More specifically the invention contemplates a dental articulator in which the mold supporting portion of the upper jaw is held fixed in a body of metal of low fusibility 20 but, by reducing such a metal to a molten state, the relation of the jaws may be altered at will and secured in such altered positions by permitting said body of metal to chill.

With these and other objects in view the 25 invention consists in certain details of construction and combinations and arrangements of parts all as will hereinafter be more fully described and the novel features thereof particularly pointed out in the appended claims.

30 In the accompanying drawings illustrating the preferred embodiment of the invention,

Figure 1 is a side elevation of the assembled articulator;

Fig. 2 is a top plan view thereof; and

35 Fig. 3 is a perspective detail view of portions of the upper jaw of the articulator.

The jaws or denture supporting members of the articulator may, in most respects, take any desired form, especially the connection 40 for securing the dentures to said jaws. For this reason, these details are neither shown nor described. Suffice it to say that the articulator comprises a lower jaw 10 for the lower denture, said jaw being formed with rearward extensions 11 in which the upper

jaw is pivotally mounted. Any suitable pivot means may be utilized but in the present instance depending extensions 12 are formed with conical recesses adapted to receive the conical or tapered ends of pivot pins 13 threaded through extensions 11 and locked in place by nuts 14.

In accordance with the present invention the upper jaw is normally held against side-wise and forward and backward movement, 55 relatively to the lower jaw, by a portion thereof being embedded in a body of metal that can be readily rendered fluid for the purpose of permitting such relative movement of the upper jaw. The point at which this fusible 60 connection is made can be varied but preferably the upper jaw is composed of two separable sections,—the denture supporting section 15 and what will be termed the pivot section 16 formed as a continuation of the pivoted extensions 12. These two sections, the denture supporting section and the pivot section are adapted to be secured together by a projection 17 on the former being embedded 65 in a body of metal 25 of low fusibility carried in a small receptacle 18 of thimble-like formation on the latter. As shown, a plate 19 fixedly attached to pivot section 16 by a screw 20 projects to the rear of extension 12 at which point it is formed with the receptacle 70 18. Likewise, section 15 is provided with a rearward extension 21, at the rear of which is the projection 17. If desired, said projection 17 may be provided with a hole 22 and recesses 23 for keying in of the metal 25 when the latter chills, thereby firmly securing the projection in said metal.

In accordance with usual practice there is a cross piece 24 between extensions 11, said cross piece having an adjustable screw 26 threaded therethrough adapted to engage the under surface of pivot section 16 of the upper jaw for limiting the closing movement of said jaw.

The operation of the articulator is as follows: The dentures are finished and placed on the articulator with the plaster in centric position as indicated in dotted lines in the accompanying drawings. The lower denture is then removed and two bite-rims, the height of the lower denture, are made of modeling compound. Plaster is then mixed and placed on the bite-rims and after the plaster has set one of said rims is placed in the lower jaw of the patient who moves the jaw from side to side until registrations are made in the plaster by thus giving an indication in the plaster in the bite of the lateral movement of the lower jaw in relation to the upper denture. This bite rim is then removed and the other substituted whereupon the patient's jaw is moved forward and back until registrations are made in the plaster indicating the forward and back motion of the lower jaw with relation to the upper denture. These bite-rims bearing the registrations thus made constitute permanent records of the motions of the condyles in the working bite. The bite rim is then placed on the lower jaw of the articulator and the fusible metal brought to a molten condition by applying to the receptacle 18 the flame of a gas burner such as generally used in dental offices. The upper jaw and denture can then be freely manipulated or moved in any direction with respect to the bite-rim until it registers with any desired point of said rim after which the metal 25 is allowed to chill and thus hold the jaws of the articulator at any desired point with relation to the bite-rim. The bite-rim is then removed from the articulator and the lower denture substituted and the spot grinding operation performed to balance the occlusion. By repeatedly melting and chilling the metal 25 all intermediate and extreme points can be made to check.

With the present articulator, the relation of the jaws or of the models on the articulator may be altered without the loss of the time element involved in waiting on plaster to set and such changes can be made while perfecting the occlusion of the teeth. Furthermore, the use of the present invention permits the individual motion to be checked on a plain line articulator.

What is claimed is:

1. In a dental articulator, the combination of a lower jaw, a sectional upper jaw having one section pivotally connected to said lower jaw, a receptacle fixed on said pivoted section of the upper jaw, said receptacle being capable of retaining in liquid form a readily fusible metal solid at normal room temperatures when the articulator is in its normal upright position, and a projection on the other section of said upper jaw extending into said receptacle whereby the jaw sections are rigidly connected together when said metal is solidified but may be disconnected

by the application of heat to the receptacle sufficient to liquefy said fusible material.

2. In a dental articulator, the combination of a lower jaw, a sectional upper jaw, a pivotal connection between said jaws, and a receptacle on one of said jaws capable of retaining in liquid form a readily fusible metal when the articulator is in its normal upright position, a portion of the other jaw extending into the receptacle and held rigidly upon solidification of the material in the receptacle.
